United States Patent

Des. 235,574
Patented June 24, 1975

235,574

HEAD SUPPORTED FLASHLIGHT

Donald E. Willis, 621 W. State St., Rockford, Ill. 61101,
and Robert P. Hohm, Rockford, Ill.; said Hohm as-
signor to said Willis

Filed Sept. 4, 1973, Ser. No. 393,949

Term of patent 14 years

Int. Cl. D26—02

U.S. Cl. D48—24 A

FIG. 1.

FIG. 2.

FIG. 3.

FIG. 4.

FIG. 5.

FIG. 6.

FIG. 1 is a perspective view of a head supported flashlight incorporating our new design.

FIG. 2 is a front elevational view of the flashlight.

FIG. 3 is a side elevational view of the flashlight.

FIG. 4 is a fragmentary top plan view of the flashlight.

FIG. 5 is a rear elevational view of the flashlight.

FIG. 6 is a fragmentary bottom plan view of the flashlight.

The temples are fragmentarily shown in FIGS. 4 and 6 for convenience of illustration.

We claim:

The ornamental design for a head supported flashlight, as shown and described.
